SECTIONAL PIER
Don A. Dally, P.O. Box 181, Pillager, Minn.
Filed Mar. 28, 1961, Ser. No. 98,904
2 Claims. (Cl. 61—49)

This invention relates to waterfront structures, such as piers or docks. Conventionally, these are built up step by step, using piles, timbers and planking, or by casting concrete in place. Both of these methods are time-consuming and expensive, and prohibitively so to people in moderate financial circumstances.

It is therefore a prime object of the invention to lessen the difficulty of constructing a pier or dock, at the same time reducing the over-all cost. Another object is to provide a pier which, while easy of erection with a minimum of required manpower, is also susceptible of assuming a variety of arrangements with no difficulty beyond that involved in a pier of the simple form represented by a single rectangle. Other objects include ready conformability to the marine bottom, and simple adjustment of the height of the platform.

These and other objects, which will be apparent to those skilled in the art, are accomplished by the present invention, which may be briefly described as comprising a series of identical, preformed, rectangular blocks, constituting platform sections, having a series of openings for sliding reception of upright supports, including height-adjusting means, and the blocks having, on opposite sides, complementary interlocking means, whereby they may be connected serially, with the pairs either in alignment, or at right angles to each other.

For a detailed description of the invention, reference is made to the following specification, as illustrated in the drawings, in which:

FIGURE 1 is a perspective view of the pier in place at a waterfront, showing an arrangement with a 90° shift of direction in the platform, to provide a protective L form.

FIGURE 2 is a sectional view through an adjacent pair of platform sections, taken along the line 2—2 of FIGURE 1.

FIGURE 3 is a sectional view taken along the line 3—3 of FIGURE 2, and showing the underside of the platform sections.

FIGURE 4 is a sectional view taken along the line 4—4 of FIGURE 3, showing a detail of one supporting upright.

FIGURE 5 is an exploded view, in perspective, of an upright and its associated, supporting collar, and showing a modified bottom support.

FIGURE 6 is a fragmentary view, in elevation, of the lower end of the upright of FIGURE 5, with the bell-bottom shown in section, and

FIGURE 7 is a view similar to FIGURE 4, showing a modified arrangement of the collar.

Referring to the drawings by characters of reference, the platform of the pier comprises a series of identical rectangular, block sections, of molded, high impact, synthetic plastic, or tough glass, five in number as shown, and indicated, respectively, by the numerals 10, 12, 14, and 11, 13, the first three forming an arm extending perpendicularly from the bank, and the last two forming an arm extending at right angles to the first arm, to provide an L form in the platform. While the sections have been indicated by different numbers for proper identification in the several views, it will be understood that all are of identical size and shape, for complete interchangeability. The color and opacity of the blocks may be varied, as desired.

Considering section 10, which shows in each of views

2

1, 2, 3 and 4, the preferred form is oblong, with long sides 16, 18, and short sides 20, 22. In order to reduce the weight and expense, while not only maintaining, but improving the strength of the platform unit, the full thickness of the unit is realized only in the four side, marginal portions 17, 19, 21, 23, and in two diagonal ribs 23, 25, the balance of the unit being hollowed out on the underside, in four, general triangular areas, 26, 27, 28, 29. The thickness will depend, of course, on the over-all dimensions of the block, with a view to resistance to bending or rupture. The full thickness of the block is also maintained at the corners, in cylindrical bosses 30, 32, 34, 36, providing areas of dwell, which have central bores 38 to receive the circular rods 39, preferably of metal, and corrosion resistant, which serve as piles. With bores 38 received on the rods, the actual support of the platform section is provided in a flanged, metal collar 40, secured to the rod by a set screw 41. The latter may have a forced penetration engagement with the rod, or the rod may be provided with a series of holes for the screw, either case permitting selective location of the collar, along the rod. The lower end of rod 39 is pointed, as at 42, for ready penetration of the bottom. For spans of excessive length, more than four rods may be required, but generally speaking, four rods should suffice for a span of up to 8 feet.

For coupling of the platform sections, each has complementary, interlocking units on opposite ends of each of its pairs of parallel sides. Thus, at the left side 20 of unit 10, there is a centrally located, rectangular, protruding tab 44 with a rectangular, through opening 46, which, as seen in FIGURES 1 and 2, has its underside above the level of the lowermost plane of the block, leaving a shoulder 48 in the plane of the side 20. The complementary feature, at the right end of the block, comprises a centrally located rectangular, rabbeted recess 50 in the upper corner of side 22, resulting in a lower supporting shelf 52. The recess 50 is of a size to snugly receive tab 44, and the shoulder 52 of the recess has a rectangular, upstanding boss 54 sized to be snugly received in opening 46 of tab 44, the under side of the latter dwelling on shoulder 52 of the recess. Since the main support of the platform is on the collars 40, the interlocking units need not have any great size or strength, their main function being to resist separation of the sections in the plane of the platform, although the interlocking feature do inherently possess some degree of resistance to any tendency of the individual sections to sag individually under concentrated load.

The description given above for the interlocking units applies identically to a recess 56 and a mating tab 58, carried medially of the respective, opposite, long sides 16, 18 of the section 10. It will thus be seen that from any block in a chain, the structure may be branched out, in a 90° departure, simply by mating the end tab or recess of a block, as the case may be, with the side recess or tab of the preceding block, rather than at the end.

In order to provide a non-skid feature, as well as easy drainage, while at the same time lowering the materials cost, the block units are preferably provided with a series of perforations 60, and, of course, these may be arranged in ornamental patterns, if desired. The number of possible holes will be limited by strength requirements.

With the foregoing description, the manner of erecting the pier will be more or less apparent, and is susceptible of variation. For instance, the rods 39 may be spotted in place, and the corner holes of the pier sections dropped over them to dwell on the collars 41, the latter being adjustable for final positioning. Or, the collars may

be tentatively located on the rods, the sections slipped onto the rods, and the system lowered, effecting both the interlocking and the anchoring of the rods, followed by final adjustment of the collars. Another variant would be to couple the section to an erected section, manually supporting the outer end of the new section until the posts have been inserted and contacted the bottom, followed by securing of the collars at the proper level.

Not only is the system easy of erection and capable of variety of pattern, but is possessed of a further important attribute in that damaged sections may be easily replaced, and at low cost. Also, the shape of the pier may be varied from time to time.

FIGURES 5 and 6 show a modification wherein, the bottom-engaging end of the supporting, upright rods, instead of a conical point, comprises a downwardly open semi-spherical shell, or bell, 62, having an upper, central boss 64 with a frusto-spherical socket, snugly receiving a ball 66 carried on a central shank 68 on the lower end of rod 39. This form avoids the excessive, and progressive penetration which might ensue from the use of a pointed rod in unusually soft bottom material, and yet provides satisfactory anchorage at low penetration since any tendency to move sidewise is resisted by the resultant forces which tend to push the bell further into the bottom.

In the modification shown in FIGURE 7, the metallic collar 40 has, as an incident of manufacture, its flanged end embedded in the pier section, concentric with hole 38, and with its lower end extending downwardly to accommodate the set screw 41. This reduces the number of distinct parts to be shipped, handled, and manipulated, from three to two, and therefore contributes to efficiency from several standpoints.

Whereas certain preferred embodiments have been shown and described, various other modifications will be apparent to those skilled in the art, in the light of this disclosure, and the invention should not, therefore, be deemed as limited, except insofar as shall appear from the spirit and scope of the appended claims.

I claim:

1. For use in a sectionalized pier structure, a unit for chainwise coupling comprising a rectangular block having a first, generally planar face, and an opposite face with co-planar, marginal portions on its four sides extending downwardly from said opposite face, and diagonal webs extending downwardly from said opposite face, with recessed areas bounded by said portions and said webs, said block having perforations in said recessed areas, and bores in corner areas common to adjacent pairs of said marginal portions, a rectangular tab on one side of said block, medially thereof, extending therefrom, and extending depthwise from said first face to a plane inwardly of the plane of said marginal portions, and said tab having a rectangular, through opening depth-

wise, the opposite side of said block from said one side having a rabbeted recess in its upper corner, sized and disposed in complementary relation to said tab, including a rectangular boss extending upwardly through the recess to said first planar face and adapted to mate with the opening in the tab, whereby the recess of one block may receive the tab of another, in interlocking relation, and the other two sides of said block, respectively, having a recess and a tab of structure identical with the first mentioned recess and tab.

5 2. For use in a sectionalized pier structure, a unit for chainwise coupling comprising a rectangular block having a first, generally planar face, and an opposite face with co-planar, marginal portions on its four sides extending downwardly from said opposite face, and diagonal webs extending downwardly from said opposite face, with recessed areas bounded by said portions and said webs, said block having bores in corner areas common to adjacent pairs of said marginal portions, a tab on one side of said block, medially thereof, extending therefrom, and of a thickness less than the maximum thickness of said block, and having a through opening depthwise, the opposite side of said block from said one side having a rabbeted recess in its upper corner, sized and disposed in complementary relation to said tab, and having a boss extending upwardly through the recess to said first planar face and adapted to mate with the opening in the tab, whereby the recess of one block may receive the tab of another, in interlocking relation, and the other two sides of said block, respectively, having a recess and a tab of structure identical with that of the first-mentioned recess and tab.
